(57) **CLAIM**

The ornamental design for an iontophoretic device for application to the brow/forehead of a person, as shown and described.

DESCRIPTION

FIG. 1 is a front perspective view of an iontophoretic device for application to the brow/forehead showing of our new design;

FIG. 2 is a rear perspective view thereof;

FIG. 3 is a front elevational view thereof;

FIG. 4 is a rear elevational view thereof;

FIG. 5 is a left side profile view thereof;

FIG. 6 is a right side profile view thereof;

FIG. 7 is a top view of the device thereof;

FIG. 8 is a bottom view of the device thereof;

FIG. 9 is a front perspective view of another embodiment of an iontophoretic device for application to the brow/forehead;

FIG. 10 is a rear perspective view thereof;

FIG. 11 is a front elevational view thereof;

FIG. 12 is a rear elevational view thereof;

FIG. 13 is a left side profile view thereof;

FIG. 14 is a right side profile view thereof;

FIG. 15 is a top view of the device thereof; and,

FIG. 16 is a bottom view of the device thereof.

The broken lines and unshaded regions enclosed by broken lines depict portions of the device that form no part of the

claimed design.
